UNITED STATES PATENT OFFICE

120,363

DESIGN FOR A BATH MAT

Frank Sudell, Roxborough, Pa., assignor to Kurdistan Rug Corporation, Philadelphia, Pa.,
a corporation of Delaware

Application December 20, 1939, Serial No. 89,044

Term of patent 3½ years

To all whom it may concern:

Be it known that I, Frank Sudell, a citizen of the United States, residing at Roxborough, in the county of Philadelphia and State of Pennsylvania, have invented a new, original, and ornamental Design for Bath Mats, of which the following is a specification, reference being had to the accompanying drawing, forming part thereof.

The figure is a plan view of the bath mat showing my design.

I claim:

The ornamental design for a bath mat, as shown.

FRANK SUDELL.
